Patented July 6, 1909.

Fig. 1.

UNITED STATES PATENT OFFICE.

THOMAS C. NIXON, OF CHICAGO, ILLINOIS.

ELECTRIC LOCK.

No. 926,890.

Specification of Letters Patent. Patented July 6, 1909.

Application filed February 19, 1908. Serial No. 416,642.

To all whom it may concern:

Be it known that I, THOMAS C. NIXON, a citizen of the United States, residing in the city of Chicago, in the county of Cook and State of Illinois, have invented certain new and useful Improvements in Electric Locks, of which the following is a full, clear, and exact description.

My invention relates to certain new and useful improvements in electric locks.

The object of this invention is to provide a simple and efficient lock in which the operation of the bolt, at least in one direction, may be controlled from a distance by the use of an electric current and suitable electric apparatus. In the two forms of my invention which I have illustrated in the drawings, the bolt in one case is manually retracted as by a key and in the other automatically by a spring, and the shooting of the bolt to the locked position is controlled by the electro magnet. The features of construction by which I attain these objects form the subject matter of my invention, a description of which will appear in the course of this specification and the essential features of which will appear more definitely in the appended claims.

In the drawings Figure 1 is a side view of the preferred form of my invention with one of the sides of the lock partly broken away to reveal the operating parts within the case. Fig. 2 is a vertical cross section taken on lines 2—2, Fig. 1. Fig. 3 is a perspective view of the bolt. Fig. 4 is a diagrammatic view illustrating the electric circuit. Fig. 5 is a side view of a modified form with one side of the case removed, and Fig. 6 is a horizontal section taken in line 6—6, Fig. 5.

In Figs. 1 to 4, inclusive, 10 represents the case of the lock and 11 the removable sides, which are secured to the case by screws 12. The lock is usually secured in the door jamb or casing A, and the keeper 13, is secured in the edge of the door B. This is, however, immaterial, as the position of the parts may be reversed if so desired. Within the case 10 is a bolt 14, which is guided to slide in the case, as for instance by means of lugs 15 upon the sides 11, that extend into guide slots 16, formed in the sides of the bolt. The bolt contains a head 17 which is arranged to engage the keeper 13, when the bolt is shot into its locked position but which is retracted from the keeper whenever the door is unlocked. As shown in the preferred form, the

bolt has two lugs 18 which project laterally from the end wall 19 and bear upon the sides 11 of the case while the side walls 20 of the bolt bear against shoulders 21 that surround the lugs 18.

The bolt is shot to its locked position by suitable mechanism here shown as a spring 22 which in the preferred form is a flat spring, one end of which is riveted to the casing and the other end of which engages the bolt by means of a pin 23 secured in the bolt and perforated ears 24 upon the spring. The tension of the spring is exerted to throw the bolt toward the right, as viewed in Fig. 1, and into engagement with the keeper 13. To retract the bolt, a key C is employed the tongue of which is arranged to strike the end wall 19 of the bolt and draw the bolt back out of its engagement with the keeper.

The bolt is held in its retracted position against the tension of the spring by a movable stop here shown as an armature 25 of an electro magnet 26. As shown the armature 25, bears a shoulder in the form of a pin 27 which, when the electro magnet is deenergized, lies in the path of travel of the bolt and engages the same so as to effectually prevent movement thereof until the pin is withdrawn from such position. A spring 28, preferably constructed of phosphor bronze, is secured to the armature and bears upon one of the cores of the electromagnet thus yieldingly holding the armature away from the cores, and simultaneously holding the pin 27 in engagement with the bolt 14. If now an electric current be sent through the magnet the armature will be drawn toward the cores against the action of the spring 22 thereby disengaging the pin 27 from the bolt 14 and permitting the spring 22 to shoot the bolt into the keeper. As soon as the magnet is deenergized the armature is swung down, the pin contacting with the upper side of the bolt 14. The magnet is supported on the case in any suitable manner and is connected to binding posts 26^a from which the conducting wires 26^b lead to a push button or switch 28, a battery 29 being interposed in the circuit at any suitable point. The armature is pivoted upon the case by pins 25^a one of which is seated in a socket 25^b in the front wall of the case and the other of which is seated in a socket in a screw 25^c.

The switch or push button 28 is located at some convenient place in the building and when it is desired to lock the door the button

is pressed to close the circuit, whereby the electro-magnet will be energized and the armature swung out of contact with the bolt to release the same, thus permitting the 5 spring to shoot the bolt into engagement with the keeper. The bolt can be retracted only by use of the key and I prefer to employ a key hole upon the inner side only so that the 10 position and existence of the lock may not be detected from without.

The modified form shown in Figs. 5 and 6, is principally intended for use in connection with doors of theaters, public halls, etc., where the desideratum is to have the doors 15 locked, but in case of fire or other disturbance, that all or any number of the same be immediately and simultaneously unlocked from a common point. In this form the bolt is retracted by a spring 30 which engages a 20 washer 31 secured upon the upper end of the bolt. In this form the spring is substituted for the key in the preferred form, as it is the desideratum in this particular form that the bolt be retracted automatically whenever the 25 magnet is deenergized. The magnet 32 is interposed in an electric circuit preferably the electric light circuit of the building, and a resistance coil 33 and switch 34 are interposed in the circuit. In this form of device 30 a closed circuit is maintained to hold the bolt in its locked position and whenever said circuit is broken and the magnet deenergized, the bolt is immediately retracted by the spring. As shown, the armature 35 is made 35 of two pieces hinged together at their meeting edges, with their free ends sliding in guide slots 36 formed upon the inner walls of the case. The hinged ends of the armature are connected to the stem of the bolt, as for 40 instance by confining them between the washer 31 and a washer 37, nuts 38 being provided to secure the washer 37 in place. To prevent the armature from becoming magnetized blocks of bone 39 are inserted in the 45 ends of the cores of the magnet, which prevent the armature from coming in actual contact with the cores. It will be readily understood that by closing the circuit the magnet will be energized, the armature will 50 be attracted by the magnets and the bolt forced down against the action of the spring and the bolt will be maintained in such position so long as the magnet remains energized. If now for any reason it is desired that the 55 door be unlocked the switch 34 is thrown, thereby breaking the circuit, and deenergizing the magnet. The spring 30 will instantly retract the bolt and allow the door to be opened.

I am aware that various other alterations and modifications of this device are possible without departing from the spirit of my invention, and I do not therefore desire to 60 limit myself to the exact construction shown and described.

I claim as new and desire to secure by Letters Patent.

1. In a device of the class described, the combination with a sliding bolt, and a spring for shooting said bolt into locked position, 70 of an electrically operated magnet, having means for resisting the action of the spring.

2. In a device of the class described, the combination with a bolt, and a spring for shooting said bolt into locked position of an 75 electro magnet, having an armature which is arranged to resist movement of the bolt except when said magnet is energized.

3. In a device of the class described, the combination with a bolt and a spring for 80 shooting the bolt into locked position of means for resisting movement of the bolt and a suitably controlled electromagnet arranged to actuate said resisting means to release the bolt therefrom.

4. In a device of the class described, the combination with a bolt, and a spring for shooting said bolt into locked position of an armature having a shoulder engaging said bolt to resist the action of the spring, a spring 90 tending to maintain said shoulder in engagement with the bolt, and a suitably controlled magnet operating to attract the armature and move the shoulder out of engagement with the bolt.

5. In a device of the class described, the combination with a bolt, and a spring for shooting said bolt into locked position, of an armature having a shoulder engaging the bolt to hold it in its unlocked position, a suitably operated electro magnet, for drawing said armature out of engagement with the bolt and a spring between the armature and magnet arranged to restore the armature into operative relation with respect to the 105 bolt.

6. In a device of the class described the combination with a bolt; and a spring for shooting said bolt into locked position, said bolt being formed with an integral member 110 adapted for engagement with a suitable key, whereby the bolt may be retracted from such locked position, of a suitably controlled electro-magnet having an armature operating to resist movement of the bolt toward its 115 locked position except when said magnet is energized.

7. In a device of the class described, the combination with a bolt having an integral member adapted for engagement with a suitable key whereby the bolt may be retracted from its locked position, and a spring for shooting said bolt into locked position, of a movable stop for said bolt including an armature, and a suitably controlled electro- 125 magnet operating to release said bolt from the stop.

8. In a device of the class described the combination with a bolt having a key engag- 130 ing wall adapted for engagement with a suit-

able key, by means of which the bolt may be retracted from its locked position, and a spring for shooting said bolt into locked position, of a swinging stop for said bolt, including an armature, a spring operating to hold said stop in engagement with the bolt and a suitably controlled electro magnet op-

erating upon the armature to withdraw the stop from the bolt.
